UNITED STATES PATENT OFFICE.

HERMAN H. TOLL AND FRANK C. DUFF, OF CLARINDA, IOWA.

COMBINATION WASHING-MACHINE.

1,339,588.

Specification of Letters Patent.

Patented May 11, 1920.

Original application filed December 22, 1917, Serial No. 208,461. Divided and this application filed October 13, 1919. Serial No. 330,304.

To all whom it may concern:

Be it known that we, HERMAN H. TOLL and FRANK C. DUFF, citizens of the United States of America, and residents of Clarinda, Page county, Iowa, have invented a new and useful Combination Washing-Machine, of which the following is a specification.

The object of this invention is to provide an improved construction for washing machines adapted for the combined operations of cleansing, rinsing and bluing the clothes and drying them after each of such operations.

A further object of this invention is to provide an improved construction for power washing machines having a tank in which clothes may be treated in different kinds of washing media and dried after each operation, together with means for transferring such media to and from the tank.

A further object of this invention is to provide improved means for raising a washing medium from a container to place of use in the washing machine.

A further object of this invention is to provide means for controlling the selective transfer of different kinds of washing fluids to the washing tank.

Our invention consists in the construction, arrangement and combination of elements hereinafter set forth, pointed out in our claims and illustrated by the accompanying drawing, in which—

Figure 1 is a plan illustrating our improved combination washing machine, a portion being broken away to show subjacent construction. Fig. 2 is a longitudinal section, on an enlarged scale, illustrating the pump and operating mechanism therefor. Fig. 3 is a detail vertical section, on an enlarged scale, illustrating the valve means for controlling passage of fluid from each of the containers. Fig. 4 is a detail vertical section, on an enlarged scale, at one end of the washing tank. Fig. 5 is a diagram illustrating the method of controlling the transfer of the various fluids. Fig. 6 is a side elevation illustrating our improved washing machine.

The subject matter of this invention was originally included in, but divided out of our application filed December 22, 1917, Serial Number 208,461, which eventuated into Letters Patent Number 1,305,953, dated June 3, 1919.

In the construction of the machine as shown the numeral 10 designates a frame preferably composed of angle and flat bars suitably connected and braced, and rectangular in form. In the lower portion of the frame 10 is mounted a platform 11 which carries, near one end of the frame, a prime mover such as an electric motor 12, having a motor shaft 13, extending longitudinally of the frame. In the lower portion of the frame also are mounted, preferably removably, a plurality of open topped pans or fluid containers, in this instance three in number and designated by the numerals 14, 15, 16, the pan 14 preferably being of greater capacity than the others. A cylindrical tank 17, formed of sheet metal, has centrally arranged trunnions journaled in bearings 18, 19 carried by side members at the top of the frame, said tank being adapted for either horizontal or upright position, and being shown in the latter position in Fig. 1 of the accompanying drawing, and in the former position in Fig. 6. Within the tank 17 is mounted a cylindrical, perforated sheet metal drum 20 adapted to contain clothes to be washed or otherwise treated in fluid contained in the tank. It is to be understood that both tank and drum are provided with suitable doors for access thereto, which may be of any desired and suitable construction and arrangement, a sliding door to the tank being shown in Fig. 6 and designated by the numeral 46. The drum is adapted for oscillating rotary movement within the tank 17 when said members are in the horizontal position, to agitate and treat the contents of the drum in fluid contained in the tank. Suitable mechanism, designated generally by the numeral 21, is provided for performing this operation, and is driven by the motor 12 under control of a clutch lever 44. This mechanism forms no part of our present invention but is illustrated, described and claimed in our companion application filed October 13, 1919, Serial Number 330,303, to which application reference hereby is made. The drum 20 also is adapted for continuous rotary motion within the tank at a high rate of speed, to dry or remove fluid from the contents of the drum by centrifugal force. This mechanism is located directly beneath the tank at the center of the frame, and is designated by the numeral 22; such mechanism also being driven from the motor 12 under control of the operator.

through a clutch lever 45. This mechanism forms no part of the present invention but is illustrated, described and claimed in our companion application filed September 5, 1919, Serial Number 321,806, to which application reference hereby is made.

A pump casing 23 is mounted on the platform 11 and is arranged in axial alinement with the motor shaft 13 which extends entirely through said casing and beyond to provide driving connection to the gearing 22. A sleeve 24 is mounted for rotation in the casing 23 and is loosely arranged relative to and outside of the motor shaft 13. Blades 25, constructed and arranged in any approved manner, are fixed to the sleeve 24 and adapted for rotation within the casing 23, and said members comprise a centrifugally acting pump adapted to convey fluid from the pans 14, 15, 16, selectively, to the tank 17. An inlet pipe 26 communicates with the casing 23 and in turn communicates with branches 27 leading from the bottoms of the respective pans 14, 15, 16. The pipes 25 are arranged beneath the platform 11 so far as may be. A branch pipe 27 leads beneath each of the pans 14, 15 and 16, and is formed with water-tight communication, by means of a packing gland 28, with the bottom of each of said pans. A tubular valve seat 29 is provided at the point of communication of each branch pipe 27 with its respective pan, which seat is directed upwardly within the pan and adapted to receive a ball valve 30 to close such communication. A stem 31 is fixed to the ball valve 30 in each instance and extends upwardly slidingly through guides or bearings 32, and terminates in a ring or eye 33, by means 40 of which the valve may be unseated manually.

A delivery pipe 34 leads from the pump casing 23 and extends upwardly and communicates with the interior of the tank 17 through one of the trunnions and bearings 18. A drain pipe 35 is connected to the pipe 26 and is provided with a suitable cut-off valve 36, the exit to said pipe being arranged beneath the platform and near the floor or other surface on which the machine is resting.

A clutch member 37 is feathered to the shaft 13 at one side of the pump casing, and is adapted for manual operation through a controlling member 38, which may be a foot lever. The clutch member 37 preferably is formed with a cone-shaped cavity at one end, adjacent the pump, adapted for frictional operative engagement with a conical end portion 39 of the sleeve 24, to effect an operation of the pump from the motor shaft.

The motor shaft 13 preferably is provided with a clutch device 40, shown conventionally, preferably of the multiple disk

type, and adapted to yield and slip when any undue or unusual strain is placed on said shaft.

The tank 17 is provided with a plurality of drain cocks in one end, in this instance three in number and designated by the numerals 41, 42, 43, each adapted to discharge fluid contents of the tank to one of the pans 14, 15, 16 when the tank is in upright position. 75

In practical use suitable washing fluids are placed in the pans 14, 15, 16, as for instance suds, rinse and blue waters, the respective valves 30 having been closed, as well as the drain cocks 36, 41, 42 and 43. 80 Articles to be washed are placed in the perforated drum 20, the doors are closed, the tank 17 placed in horizontal position, the motor 12 started, and operative engagement of the pump effected by manipulation of the control 38. The valve 30 of the pan 14, for instance, is raised by lifting the stem 31, and is held in such position while the pump carries suds water from said pan through its branch pipe 27 to the pump casting and thence to the tank 17 through the delivery pipe 34. When the pan 14 has been emptied, or sufficient of its contents conveyed to the tank, the pump is stopped and engagement of the driving mechanism 21 90 with the drum effected in the manner provided, through the controlling lever 44, and the drum is rotated alternately in opposite direction for a time sufficient to cleanse the articles therein. Then the mechanism 21 is 100 disconnected and the tank is turned to the upright position and operative engagement of the driving mechanism 22 effected to spin the drum and contents rapidly to the end of drying such contents by centrifugal force, 105 the moisture returning to the tank 17. The cock 41 is opened and all of the fluid in the tank and drum is allowed to return to the pan 14 by gravity, it first having been ascertained that its ball valve 30 is in closed 110 position.

This operation is repeated successively with respect to the fluid contents of each of the pans 14, 15, 16 and the contents of the drum treated in each of said fluids successively to cleanse, rinse and blue such contents in the usual manner. If desired the washing fluids, or either of them, may be heated in the pans by placing a portable burner (not shown) therewith. 115

When the contents of the drum have thus been treated in succession in as many different fluids as are provided, or desired, the drum may be opened and the contents removed and placed on the line for further drying. Or if desired the drum may be spun sufficiently, after the last operation, to remove practically all of the moisture from the clothing so that it may be ironed without further drying. 125 130

Then other batches of clothes may be similarly introduced to the drum and treated in a like manner, after which all of the valves 30 may be opened and the drain 5 cock 36 opened to permit the contents of all of the pans to flow to the sewer or other place provided for the waste water.

It should be observed that it is not necessary for the operator to handle the clothes 10 from the time they are placed in the drum until they have been entirely cleansed, rinsed, blued and dried, and neither is it necessary for him to lift or handle any of the fluids or to place his hands in them. It 15 is only for him to guide the machine in its work by shifting the respective levers and controls to effect the desired operations in the desired sequence.

The valves 30 tend to seat automatically 20 when the stems are released, so that fluid is not unintentionally drawn from either of the pans.

We claim as our invention—

1. A washing machine, comprising a tank 25 adapted to be turned to a horizontal or vertical position, a drum rotatably mounted therein, a plurality of pans, a pump connected with the tank for supplying fluid thereto, means for connecting the pump 30 with either of the pans, and means for draining the contents of the tank to either of said pans when said tank is in a vertical position.

2. A washing machine, comprising a tank adapted to be turned to either horizontal 35 or vertical position, journals on which the tank is mounted to be swung through an arc of ninety degrees from one position to the other, one of said journals being tubular, a delivery pipe extending through the 40 tubular journal to supply fluid to the tank, a drum rotatably mounted in the tank, a pump connected with the delivery pipe, a plurality of pans, and means for connecting the pump to either of said pans to deliver 45 fluid from the latter to the tank.

3. A washing machine, comprising a tank adapted for horizontal or vertical position, journals on which the tank is mounted to be swung through an arc of ninety degrees from one position to the other, one of said 50 journals being tubular, a delivery pipe extending through the tubular journal to supply fluid to the tank, a drum rotatably mounted in the tank, a pump connected with the delivery pipe, a plurality of pans, an operating motor, and means for coupling and uncoupling the pump and the motor, the liquid contents of said tank being adapted to be drained selectively into said pans when the tank is in vertical position. 55

4. A washing machine, comprising a frame, a tank pivoted therein and adapted for horizontal or upright position, a plurality of pans carried by said frame below said tank, a delivery pipe leading to said tank, a pump connected to said delivery pipe, a valve-controlled pipe leading from each of said pans to said pump, and means for conveying fluid contents of said tank to either 60 of said pans. 70

5. A washing machine, comprising a frame, a tank pivoted therein and adapted for horizontal or vertical position, a plurality of pans carried by said frame below said tank, a delivery pipe leading to said tank, 75 a pump connected to said delivery pipe, valve-controlled pipes leading from the respective pans and connected to a common pipe communicating with said pump, spaced valve-controlled means for draining contents of said tank to either of said pans when the tank is in upright position, and a valve-controlled drain pipe communicating with said common pipe, whereby the tank, 80 pans and pump may be drained. 85

Signed at Clarinda, in the county of Page and State of Iowa, this 12th day of September, 1919.
